UNITED STATES PATENT OFFICE

CURT F. REIS, OF BELOIT, WISCONSIN, ASSIGNOR TO FAIRBANKS, MORSE & COMPANY, OF CHICAGO, ILLINOIS, A CORPORATION OF ILLINOIS

MAGNETO

Application filed November 27, 1931. Serial No. 577,682.

My invention relates to magnetos and particularly to magnetos of the type employing a permanent magnet rotor.

One object of my invention is to produce a magneto in which the over-all length of the rotor may be reduced, while for the same length of rotor a much stronger magnetic field may be obtained.

Another object is to provide a short efficient rotor which may be assembled in fixed permanent form without bolts, screws or welding.

Still another object is to produce a rotor which may be constructed almost entirely of non-annealed steel, and in which parts may be magnetized efficiently after the rotor is assembled.

Other objects include the production of a special stator structure which is adapted to operate efficiently with short rotors such as are contemplated by my invention; special pole piece structure aiming toward obtaining efficient magnetic circuits, and numerous other objects and advantages which will be apparent to those skilled in the art, from a reading of the following specification in conjunction with the accompanying drawings in which:

Figure 1 is a perspective view of one form 30 of assembled rotor embodying my invention.

Figure 2 is a section on line 2—2 of Figure 1.

Figures 3 and 4 are sections taken on lines 3—3 and 4—4, respectively, of Figure 2.

Figure 5 is a fragmentary section taken on line 5—5 of Figure 3.

Figure 6 is a vertical longitudinal section of one form of magneto embodying my invention, the section showing the relation between the rotor and stator pole pieces.

Figure 7 is a view partly in elevation, and partly diagrammatic showing the relation between the rotor and stator parts after they are assembled; and

Figure 8 is an enlarged detail view of a portion of the stator laminated structure.

Referring to Figure 2 of the drawings the reference character 11 designates a shaft, having a shoulder 12 adjacent one end, a threaded portion 13 near the other end, and the usual

tapered and threaded drive-end portion beyond the thread 13. Threaded over the shaft 11 and secured thereon, as by keys 14, are two non-magnetic disks or end-plates 15 and 16. The disk 15 is imperforate, except for the shaft opening, while disk 16 contains a plurality of perforations or openings 17 at spaced intervals.

In contacting relation and coaxially with the disk 15, are a permanent magnet plate 18, and a non-magnetic supporting plate 19, both of which are keyed to shaft 11 by the same key that holds disk 15. The supporting plate 19 is locked to plate 18 by overhanging lugs 21 (see Figures 3 and 5) and contains perforations 22 which are in line with the perforations 17 in plate 16.

The plate 19 and disk 16 support bar magnets 23, here shown as of cylindrical form but this, while preferred, is not essential. These bar magnets abut the permanent magnet plate 18 at one end of the rotor so as to form a continuation of the magnetic circuit of this magnet, while at the other end they fit into and pass through the perforations 17 in disk 16.

The magnets 23 carry laminated pole-pieces 24 and 24^a made up of thin iron or steel plates. Pole piece 24 surrounds the like poles of two of the magnets 23, while pole piece 24^a surrounds the opposite poles of the two opposite magnets 23. Obviously each pole shoe must connect like poles in each instance and, although I have shown a two-pole structure my invention is applicable to other arrangements.

The pole shoes 24 and 24^a may contact with disk 16, but ordinarily the length of these shoes will be less than that of the magnets between plate 19 and disk 16. In such a case I provide sleeves 25 about each bar and which fill the space between the pole pieces and the plate 19. Consequently when disks 15 and 16 are drawn together the sleeves and pole pieces are compressed into a rigid fixed assembly. As here shown a gear 26 is also keyed to shaft 11 and the whole assembly is secured to the shaft 11 by a nut 27 engaging thread 13 and preferably seating in a socket 28 in the space of gear 26. In this way the entire rotor

structure is held between shoulder 12 and nut 27, and the bar magnets are accurately supported in spaced relation in the perforations of plate 19 and disk 16.

5 The over-all length of the rotor is small because the bar magnets abut and form a continuation of the magnetic circuit of permanent magnet plate 18. The plate 18 may be magnetized before the rotor is assembled 10 but bar magnets 28 may be magnetized after assembly by bringing their exposed ends which project through disk 16 into direct engagement with the magnetizing poles. In the usual arrangement it is necessary to magnetize the poles through an air gap with consequent loss in efficiency because of the high reluctance introduced into the magnetizing field. With my structure it becomes practical 15 to magnetize the poles after assembly and to do it effectively by direct contact with the source of magnetizing flux.

It will be obvious that by varying the number of laminations in the pole pieces 24 and correspondingly varying the length of sleeves 25, the effective length of the pole pieces may be made to suit any desired conditions.

In employing rotors embodying my invention I prefer to make use of a stator structure as is illustrated in Figures 6, 7 and 8. Referring now to Figure 8, the reference character 31 designates a generating coil containing the usual coil bridge 32. This bridge is supported on and is in direct magnetic relation with two similar pole pieces 33. Since 35 these pole pieces are of identical structure only one of them is shown.

These pole pieces are made up of laminations of iron or steel, and preferably comprise alternate long laminations 34 (see Figure 8) 40 and short laminations 35. The long laminations 34 extend throughout the length of the pole piece into contact with bridge 32, while the short ones 35 extend only a short distance or to a deflected portion or shoulder 36. The 45 object of this arrangement is to make the pole piece wider at the bottom where it is in magnetic relation with the rotor than at the top where it meets the coil bridge. This result is accomplished by interspersing a short lamination 1 between each pair of long ones; and then contracting the pole piece above point 36. In order to strengthen the structure, especially after the squeezing or contracting 50 operation it is preferred to use thicker long laminations 37 at spaced intervals. As here shown every fifth long lamination is thicker. I am aware that it is not new to intersperse long and short laminations in order to increase the flux concentration in the coil bridge, 55 but I believe I am the first to improve this combination by interspersing heavier laminations at intervals. These heavier laminations not only stiffen the structure, but they also tend to prevent ruptures during the contracting process.

The result of this arrangement is to produce a strong efficient structure in which the flux concentration is increased and the secondary voltage generated, therefore, also increased. A magneto embodying this structure is especially applicable to use in connection with high compression engines in which a hot spark is essential.

Although I have herein shown and described only one form of magneto embodying my invention, it will be obvious that changes may be made in the details, within the scope of the appended claims, without departing from the spirit and scope of the invention.

What I claim is:

1. A rotor for a rotating field type of magneto, including a shaft, a plate assembly including a permanent magnet plate, a non-magnetic plate and locking means associated with one of said plates and engaging the other thereof, for preventing relative rotational movement between said plates, a plurality of permanent bar magnets in magnetic contact with said magnet plate and forming a continuation of the magnetic circuit thereof; and means for securing said plate assembly against rotation on said shaft.

2. A rotor for a rotating field type of magneto, including a shaft, a perforated end plate detachably secured to said shaft, a plate structure consisting of a permanent magnet end plate, a non-magnetic plate having lugs arranged to engage in locking relation said magnet plate, and a plurality of permanent bar magnets spaced from each other but each abutting said magnet end plate and forming a continuation of the magnetic circuit thereof, and each of said magnets having one of its ends projecting through one of the perforations in said end plate.

3. A rotor for a rotating field type of magneto, including a shaft; a perforated end plate of non-magnetic material detachably secured to said shaft near one end thereof; a plurality of spaced permanent bar magnets, each supported at one end in a perforation in said plate; pole shoes bridging certain of said magnets; a plate structure including a permanent magnet plate secured to said shaft at the other end and abutting the ends of the bar magnets; spacers between the plate structure and pole shoes, and means coating with the shaft, spacers and end plate for clamping the plate structure to the bar magnets, and clamping the pole shoes in assembled relation to the magnets and end plate.

4. A rotor for a rotating field type of magneto, including a shaft, a shoulder adjacent one end of said shaft, a perforate non-magnetic end disc detachably secured to said shaft adjacent said shoulder, an end plate structure consisting of a pair of non-magnetic end plates detachably secured to said shaft, one of said plates being perforated and the other imperforate, a permanent mag-

- net plate disposed between the pair of non-magnetic plates and in contacting relation with said imperforate end plate, means carried by one of said plates and arranged to 5 be locked into holding relation with another of said plates; a plurality of bar magnets disposed in abutting relation to said permanent magnet plate with their other ends carried in and projecting through the per- 10 forations in said perforated end disc; laminated pole shoes threaded over and bridging certain of the bar magnets adjacent said per- 15 forated end disc; spacer sleeves carried by said bar magnets between the pole shoes and plate structure; and means coacting with said shaft, sleeves, and disc for clamping the plate structure to the bar magnets; and for clamping the pole shoes in fixed assembled relation to the bar magnets and disc.
- 20 5. A rotor for a rotating field type of magneto, including a shaft having a shoulder portion, a non-magnetic end plate with spaced apertures therein, and detachably positioned adjacent the shoulder portion; an imperforate permanent magnet plate; a plurality of bar magnets, each of said magnets having one of its ends projecting through one of said apertures and having its other end abutting said permanent magnet plate and forming 25 a continuation of the magnetic circuit thereof; pole shoes bridging certain of said bar magnets, spacer members between the pole shoes and said magnet plate, means for securing said plates against rotation relative 30 to said shaft, and permitting limited movement of said plates along said shaft, for assembly purposes.
6. A stator structure for magnetos, including an aggroupment of compressed laminations, one end of the group consisting of a greater number, and the opposite end of a lesser number of laminations, the laminations adjacent each other being closely compressed at the respective ends of the group 35 whereby there results a flux-concentrating portion of lesser thickness at the end of the group containing fewer laminations.
7. A laminated stator structure for magnetos including groups of stacked lamination- 40
- tions, each group consisting of alternate long and short laminations held in close contact, the longer laminations being extended beyond and deflected from the planes of the shorter laminations, and sheets of heavier material disposed at intervals between the longer laminations and being coextensive therewith, said sheets being shaped to conform substantially to the shape of the longer laminations the elements of each group being so assembled as to produce a portion of greater width near one end of the group, and a portion of lesser width at the opposite end of the group; the groups being related in assembly with the portions of lesser width assembled adjacent each other whereby to effect a flux concentration at the group ends of lesser width.
8. A rotor for a rotating field type of magneto, including a shaft, a permanent magnet plate; a plurality of bar magnets abutting said magnet plate and forming a continuation of the magnetic circuit thereof; laminated pole pieces embracing certain of said bar magnets at one end thereof, spacers carried by said bar magnets between said pole pieces and said permanent magnet plate; and perforate non-magnetic plates at each end of said bar magnets, each magnet thereof having its end portions seated in a perforation in each non-magnetic plate to form a rigid assembly.
9. A rotor for a rotating field type of magneto, including a shaft, a perforate non-magnetic member on said shaft, a plurality of bar magnets each supported at one end in a perforation in said member, a plate assembly 100 consisting of an imperforate magnet plate, and a perforate non-magnetic plate, each bar magnet being supported in a perforation in said non-magnetic plate and in contact with said magnet plate; laminated pole shoes connecting the like polar ends of said bar magnets remote from said plate assembly; spacers between said pole shoes and said plate assembly; and means for clamping the plate assembly to said bar magnets.
